(57) **CLAIM**

I claim the ornamental design for a decorative scroll for a window, as shown and described.

DESCRIPTION

FIG. 1 is a front elevation view of a decorative scroll for a window, shown in use;

FIG. 2 is a front view of the decorative scroll for a window;

FIG. 3 is a perspective view thereof;

FIG. 4 is a side view thereof; and,

FIG. 5 is a top view thereof.

Broken lines and unshaded portions contained within broken lines are not claimed.

1 Claim, 5 Drawing Sheets
